US00D606121S

(12) **United States Design Patent**
Miller et al.

(10) **Patent No.:** US D606,121 S
(45) **Date of Patent:** ** Dec. 15, 2009

(54) **PROMOTIONAL DEVICE**

(75) Inventors: **Nicholas Miller**, London (GB); **Chris Lanman**, London (GB); **Kelly Maguire**, London (GB)

(73) Assignee: **KYP (Holdings) PLC.**, London (GB)

(**) Term: **14 Years**

(21) Appl. No.: **29/337,647**

(22) Filed: **May 27, 2009**

(57) **CLAIM**

The ornamental design for a promotional device, as shown and described.

DESCRIPTION

FIG. 1 is a side view of a promotional device showing our new design in an unfolded configuration with content inserts in a retracted state;

FIG. 2 is a second side view thereof;

FIG. 3 is a side perspective view thereof with content inserts in an extended state; and,

FIG. 4 is a front perspective view of the promotional device in a folded configuration with content inserts in a retracted state.

The tabs extending from the body of the design in FIG. 3 represent content inserts that retract into the body of the design as shown in FIGS. 1, 2, and 4.
